WILSON B. WIGLE, OF MONTEBELLO, CALIFORNIA.

WHEEL-GUDGEON.

1,349,030.

Specification of Letters Patent. Patented Aug. 10, 1920.

Application filed September 29, 1919. Serial No. 327,035.

To all whom it may concern:

Be it known that I, WILSON B. WIGLE, a citizen of the Dominion of Canada, residing at Montebello, in the county of Los Angeles 5 and State of California, have invented new and useful Improvements in Wheel-Gudgeons, of which the following is a specification.

This invention relates to wheel gudgeons, 10 and is particularly adapted to be used in connection with a bull and calf wheel, commonly used in the oil well drilling industry, for the raising and lowering of the various pipes and tools in the well.

15 It is the object of my invention to provide a gudgeon construction, which will be simple and durable, and whereby all of the bolts and fastening devices may be accessible in order that all of the parts may be 20 readily assembled and taken apart.

It is a further object of my invention to provide a construction whereby the gudgeon may be formed integral with a hub, which is of polygonal shape both exteriorly and 25 interiorly, whereby tangential wheel spokes may be readily bolted to the flat surfaces of said polygon, thereby providing an adequate bearing surface for said spokes.

Other objects will appear in the following 30 description, will be pointed out in the appended claims, and embodied in the accompanying drawings, in which:

Figure 1 represents a cross section of a drum, to which is secured my improved 35 gudgeon, parts of which are broken out and shown in section in order to more clearly show the construction.

Fig. 2 is a longitudinal section of the same, taken on the irregular line 2—2 of 40 Fig. 1.

In carrying out my invention, and by referring to the accompanying drawings, 5 represents a hollow drum preferably formed of steel tubing, over one end of which is slipped the sleeve 6, which is preferably 45 formed of a steel forging or casting, and forms part of the gudgeon. The sleeve 6 is closed at the end 7, from which projects the centrally disposed trunnion 8, which is preferably 50 provided with the bore 9, in order to impart lightness to the structure without sacrificing strength.

Projecting radially from the sleeve 6, is a plurality of webs 10, adapted to engage with 55 the inside corners of a hollow polygon 11, which is preferably hexagonal, and supports

the same. A plurality of radial webs 12, join the hub 6 with the flat inner surfaces of the polygon 11, at a point midway between its corners. The webs 12 are of shorter 60 width than the face of the polygon 11, thus allowing the opposite edges of the polygon to project beyond said webs on both of its sides, as clearly shown in Fig. 2 of the drawings.

65 The flat surfaces of the polygon 11 are each provided with a pair of oppositely disposed perforations 14 and 15, arranged in the projecting sides thereof, adapted to receive the bolts 16 and 17, which also pass 70 through perforations 18 and 19 in hub 6, and 20 and 21 in the drum 5, and perforations 22 and 23 of the tangential spokes 24, and are secured in position by the nuts 25 and 26 which hold said spokes firmly to the 75 polygon 11, as well as said sleeve to said drum.

In order to clamp the spokes 24 still more firmly to the polygon 11, I provide additional perforations 28 and 29 in said spokes 80 which register with corresponding perforations 30 and 31 arranged in the polygon 11, on opposite sides of the webs 12, adapted to receive the short bolts 32, the heads of which project into the pockets 34 formed 85 between the walls of the sleeve 6, the polygon 11 and the webs 10 and 12. By the above recited construction, it is obvious that the bolts 32 and 33 may be readily inserted into or removed from their respective perforations without the slightest difficulty.

In order that the bolts 16 and 17 may be readily placed into their respective holes, and secured in proper position, I provide the hand holes 36, which are cut into the closed 95 end 7 of sleeve 6.

The spokes 24 may extend outwardly any desired distance and be secured to the rim of the wheel (not shown) which is provided in the usual manner with grooves to receive 100 the driving cable.

By the foregoing description of my device, it will be seen that I have provided a construction which is simple, strong and durable, and which provides adequate fastening means for both securing the gudgeon to the drum, and the wheel spokes to the gudgeon, and that said fastening means are readily accessible at all times.

What I claim is:

1. A device of the class described, comprising a hollow cylindrical drum, a sleeve

provided with a closed end adapted to fit over the end of said drum, a trunnion projecting from the closed end of said sleeve, a plurality of radially projecting webs adapted to support a hollow polygon secured to said sleeve, a plurality of tangential spokes adapted to abut against the flat outer surfaces of said polygon, and bolts adapted to pass through apertures in said spokes, polygon, sleeve, and drum, for securing these parts together.

2. A device of the class described, comprising a hollow cylindrical drum, a sleeve provided with a closed end having a hand hole adapted to fit over the end of said drum, a trunnion projecting from the closed end of said sleeve, a plurality of radial webs projecting from said drum and joining with the flat inner surfaces of a hollow polygon, the edges of said polygon projecting beyond said webs on both sides thereof, a plurality of tangential spokes adapted to abut against the flat outer surfaces of said polygon, bolts adapted to pass through apertures in said spokes, polygon, sleeve and drum on opposite sides of said webs, a plurality of second-

ary radial webs joining said sleeve with the corners of said polygon, and bolts adapted to pass through apertures in said spokes and polygon arranged at points between said first and second mentioned webs.

3. A device of the class described, comprising a hollow cylindrical drum, a sleeve provided with a closed end secured to said drum, a trunnion projecting from the closed end of said sleeve, a polygonal spoke securing member secured to said sleeve by means of a plurality of radially projecting webs, and a plurality of tangential spokes detachably secured to said polygonal spoke securing member.

4. A device of the class described, comprising a hollow cylindrical drum, a sleeve detachably secured to said drum, a hollow polygonal spoke securing member secured in spaced relation to said sleeve, and a plurality of spokes secured to the outer faces of said spoke securing member.

In witness that I claim the foregoing I have hereunto subscribed my name this 19th day of September, 1919.

WILSON B. WIGLE.
